UNITED STATES PATENT OFFICE.

OTTO FISCHER, OF STUTTGART, GERMANY, ASSIGNOR TO ROBERT BOSCH AKTIEN-
GESELLSCHAFT, OF STUTTGART, GERMANY.

JERKWISE-ACTING DRIVING DEVICE FOR IGNITION APPARATUS.

Application filed October 27, 1921. Serial No. 510,702.

To all whom it may concern:

Be it known that I, OTTO FISCHER, a citizen of Germany, residing at Stuttgart, Germany, have invented certain new and useful 5 Improvements in a Jerkwise-Acting Driving Device for Ignition Apparatus, of which the following is a specification.

This invention relates in general to driving devices for ignition apparatus of the 10 kind in which a jerk-wise motion of the armature is effected by a temporary locking of a coupling half. This motion is given such a speed that the generation of an ignition spark is assured, so that the ignition 15 can be effected even at slow speed of the engine. Discontinuing the jerk-wise motion is automatically effected by centrifugal power at a certain higher number of revolutions. A spring which had been put under 20 tension on locking the respective coupling half and then produced the jerk-wise motion serves thereafter as a dragging coupling between the two halves of the driving device.

Now, concerning the known devices of this 25 kind there is that drawback connected with them that they can be employed only for one direction of motion. This drawback is obviated in and by the present invention, the gist of which consists in the parts effecting 30 the release at the temporary locking serving also as abutments for the dragging coupling at normal running of the engine. Besides the possibility of employing the same model for rotation to the right, as well as to the 35 left, without a change of the details, the further advantage of a greater simplicity of the apparatus is attained.

In order to make my invention clearer, I refer to the accompanying drawing, in 40 which similar letters of reference denote similar parts throughout the several views, and in which Figure 1 is a front view of a device; Figure 2 is a similar illustration showing the same parts in another position; 45 and Figure 3 is a side view, one of the coupling halves being shown in axial section and the two halves being a little separated one from the other.

The driving device consists of two coupling halves *a* and *b*, of which the one (*a*) which is the driving half has a driving cog-wheel *c* whereas the other (*b*) is firmly connected with the armature shaft *d* of the ignition apparatus *e*. The coupling halves are

connected with each other by a spring *f*, one 55 end of which is attached to a projection *g* of the half *a*, and the other end of which is attached to a projection *r* of the half *b*. The objects of this spring are, firstly, to drag the coupling half *b* which is that retained by 60 the temporary locking sufficiently quickly after it has been released; secondly, to bring the coupling halves in direct contact with each other at normal running of the ignition 65 apparatus.

The coupling half *b* carries levers *g* which are supported in stays *p* and are eccentrically-mounted with respect to the shaft *d* and movable upon bolts *h*. The levers *g* have lugs *i* which co-operate with an abutment *m* of the casing *k* of the ignition apparatus, and each has at the inner side of its end a curved surface *n* which co-operates with a projection *o* provided on the coupling half *a* and serving for releasing the 75 levers at the temporary locking.

The manner of operation of this device is as follows:

When at rest, the various parts are in the position shown in Fig. 1. The projections *o* are in direct and intimate contact with the stays *p* owing to the tension or pull of the spring *f*. When at slow running of the ignition apparatus the lug *i* of a lever *g* contacts with the abutment *n*, the coupling 80 half *b* is held fast, whereas the half *a* continues its rotation under the influence of the driving power, thus putting the spring *f* under tension. When lefthand projection *o* of the half *a* contacts with the curved surfaces of the lefthand (upper) lever *g* (Fig. 85 2), this lever is lifted until its lug *i* disengages the associate abutment *m*, whereby the coupling half *b* is caused to suddenly 90 follow the coupling half *a* under the pull 95 of the spring *f*, until the projections *o* again contact with the stays *p*. This is repeated until the internal combustion engine has commenced to start and the speed of the 100 ignition apparatus has become so great that the levers *g* are flung outwards under the centrifugal power then arising.

From this moment the levers *g* are out of engagement with the abutment *m* can therefore no longer function to hold or stop 105 the coupling half *b*. The two halves *a* and *b* are now connected with each other by a drag-coupling in that the abutments *o* lie

close to the stays *p* under the action of the spring *f* and remain in this position during the normal running of the engine. This arrangement, it is to be observed, prevents an 5 overrunning of the driven part of the magneto with respect to the driving part during the normal running of the engine, such as might otherwise occur by momentum of the driven part of the magneto when the speed 10 of the engine and hence the speed of rotation of the driving part for the magneto is reduced.

In order to employ the arrangement also for the other direction, the only alterations 15 necessary are, firstly, to take the levers *g* off their pivots *h*, turn each of them so as to make it point to the opposite direction, and replace it upon its pivot; secondly, to mount the spring *f* in the opposite direction 20 about the periphery of the parts *a* and *b* so as to make it draw the projections *o* against the other side of the stays *p*.

The special construction of the various 25 parts entering into the combination shown and described by way of example is not an essential characteristic of the invention. There may be changes of the construction without change of the effect. The coiled spring shown may, for instance be replaced 30 by another kind or configuration of spring,

and instead of the levers *g* ball or other fly masses may be made use of.

Having now described my invention, what I desire to secure by a patent of the United States is:

A jerk-wise acting driving device for ignition apparatus comprising, in combination, a driven coupling part, a driving coupling disc, a spring connecting the said coupling part and the said coupling disc, spaced stays on the said coupling part, levers pivoted on the said stays and extending into the space therebetween, a fixed abutment on the ignition apparatus adapted to engage said levers in locking position to hold said coupling part immovable, projections from said coupling disc extending into the space between said stays and adapted in one driving movement of said disc to disengage said levers from said locking position, said spring 40 being adapted to hold said coupling part in driven relation with said disc during the further driving movement of said disc and with said projections and stays in contact. 45

In testimony whereof I have affixed my 50 signature in presence of two witnesses.

OTTO FISCHER.
